UNITED STATES PATENT OFFICE.

WILLIAM SULWIN GANDER, OF RUSSELL, PENNSYLVANIA.

WAGON-BRAKE-OPERATING MEANS.

Application filed April 9, 1923. Serial No. 630,928.

To all whom it may concern:

Be it known that I, WILLIAM SULWIN GANDER, a citizen of the United States, residing at Russell, in the county of Warren 5 and State of Pennsylvania, have invented certain new and useful Improvements in Wagon-Brake-Operating Means; and I do declare the following to be a full, clear, and exact description of the invention, such as 10 will enable others skilled in the art to which it appertains to make and use the same.

My invention relates to improvements in wagon brakes, and has for its object to provide a simple and inexpensive, yet a highly 15 efficient and reliable operating mechanism for the brakes which will be automatically brought into play when the load has a tendency to move forwardly upon the draft animals, provision being made however where- 20 by the brake operating means may be held against action when backing the wagon.

With the foregoing in view, the invention resides in the novel subject matter herein- 25 after described and claimed, the description being supplemented by the accompanying drawing.

Figure 1 is a plan view of a portion of a wagon running gear equipped with my invention.

30 Figure 2 is a view similar to Fig. 1 showing a different position of parts and illustrating certain elements in horizontal section.

Figure 3 is a longitudinal sectional view 35 as indicated by line 3—3 of Fig. 1.

Figure 4 is a transverse sectional view on line 4—4 of Fig. 1.

Figure 5 is a perspective view of certain 40 parts of the brake operating means and the bracket by means of which they are attached to the front axle or other desired part of the running gear.

I have shown my invention in connection 45 with a well known form of wagon having the usual front axle 1, front hounds 2 and a tongue 3.

The numerals 4 designate a pair of sub- 50 stantially rectangular horizontally spaced frames whose inner opposed sides are intended to slidably receive the tongue 3 therebetween, the opposite sides of this tongue being provided with suitable wear plates 5. The outer side bars of the frames 4 converge forwardly to some extent to contact with the inner sides of the hounds 3 and they may be secured to these hounds by

any desired means, such as the bolts 6. A transverse bolt 7 passes through both of the frames 4, through slots 8 in the tongue 3 and plates 5, and through the front ends of 60 the hounds 2. Preferably, this bolt also serves to anchor the front ends of braces 9 which converge forwardly from the axle 1.

By mounting the tongue 3 in the manner described, it may slide longitudinally and 65 in the present disclosure, this sliding movement is utilized for controlling the brakes of the wagon.

The numeral 10 designates a horizontally 70 elongated metal bar adapted to contact with the front side of the axle 1, the lower edge of said bar having a short rearwardly extending arm 11 and a relatively long similarly extending arm 12, said bar and arms constituting a bracket upon which several 75 important parts of the brake operating means are mounted. The two arms 11 and 12 are secured by bolts 13 against the lower side of said axle at opposite sides of the wagon reach 14 and serve to space the bolster rest 15 the proper distance from said axle. 80

A substantially horizontal lever 16 is fulcrumed between its ends on an appropriate fulcrum member 17 which extends forwardly from the bar 10, said fulcrum member being pivotally connected to the bar if desired, as indicated at 18. One end of the lever 16 is connected by a suitable push rod or other thrust device 19, with the tongue 3, a bolt 20 being shown for loosely connecting the front end of said push rod with said tongue. The other end of the lever 16 is pivoted to a longitudinal rod 21 which 85 co-operates with a chain or the like 22 in forming a pull device suitably connected with the brakes (not shown) for operating them when pulled forwardly. In order to maintain the proper relation of parts, regardless of the angle at which the axle 1 90 may stand, I prefer to pivot a horizontal arm 23 to the rear end of the bracket arm 12 which extends rearwardly beyond the axle 1, the free end of said arm 23 being connected with the rear end of the rod 21 95 and the front end of the chain 22 or with any other suitable part of the pull device 21—22.

By employing the construction shown, it 110 will be seen that whenever the load has a tendency to run forwardly on the team, the tongue 3 will slide rearwardly, thus forcing

upon the thrust device 19 and rocking the lever 16 in such a manner as to pull upon the device 21—22, thus applying the brakes to the wagon.

5. In order to prevent rearward sliding of the tongue 3 when backing, I have provided a suitable hook 24 which is pivoted on the bolt 7 within one of the frames 4. This hook is normally out of engagement 10 with the tongue, but may be hooked over the rear end of said tongue as seen in Figs. 1 and 3, when the wagon is to be backed.

Excellent results have been obtained from the construction herein disclosed and it is 15 therefore preferably followed. However, within the scope of the invention as claimed, numerous changes may be made.

I claim:

1. Wagon brake applying means comprising a horizontally elongated bar to abut the front side of the front axle, said bar having rearwardly extending arms adapted to be bolted to the axle, a fulcrum member extending forwardly from said bar, a lever 25 fulcrumed between its ends on said fulcrum member, a thrust device connected with one end of said lever and extending forwardly therefrom to be operated by rearward force exerted by the draft animals, and a brake 30 operating pull device connected to and extending rearwardly from the other end of said lever.

2. Wagon brake operating means comprising a lever and means for fulcruming the 35 same on the front end of the wagon running gear, a thrust device connected with one end of said lever and extending forwardly therefrom to be operated by rearward force

exerted by the draft animals, a brake operating pull device connected to and extending 40 rearwardly from the other end of said lever; together with a member adapted to extend rearwardly from the front axle of the wagon, and a movable arm pivoted to said member and connected to said pull device 45 behind its connection with said lever.

3. Wagon brake operating means comprising a bracket secured to the front axle of the wagon, one arm of said bracket being elongated to extend rearwardly from the 50 front axle; a movable arm pivoted at one end, to said elongated arm; a brake operating pull device connected to the opposite end of said arm, a lever fulcrumed on said bracket and connected at one end with said 55 pull device and a thrust device connected with the opposite end of said lever and operated by the rearward force exerted by the draft animals.

4. Mounting means for a slidable wagon 60 brake operating mechanism comprising a pair of spaced open frames secured at their outer sides to the forward ends of the wagon hounds, a tongue slidably mounted between the inner sides of said frames and having a horizontal slot, a bolt passing transversely 65 through said hounds, frames and the slot in said tongue, and a tongue holding hook pivotally and slidably mounted on said bolt within one of said frames for engagement 70 with the rear end of the tongue when the wagon is backed.

In testimony whereof I have hereunto affixed my signature.

WILLIAM SULWIN GANDER.
